(57) **CLAIM**

The ornamental design for a clam shell gun stock holder as shown and described.

DESCRIPTION

FIG. 1 is a perspective view of the clam shell gun stock holder in the deployed position;

FIG. 2 is a top plan view of the clam shell gun stock holder in the deployed position;

FIG. 3 is a rear elevational view of the clam shell gun stock holder in the deployed position;

FIG. 4 is a bottom plan view of the clam shell gun stock holder in the deployed position;

FIG. 5 is a front elevational view of the clam shell gun stock holder in the deployed position;

FIG. 6 is a right side elevational view of the clam shell gun stock holder in the deployed position;

FIG. 7 is a left side elevational view of the clam shell gun stock holder in the deployed position;

FIG. 8 is a perspective view of the clam shell gun stock holder in the stowed position;

FIG. 9 is a top plan view of the clam shell gun stock holder in the stowed position;

FIG. 10 is a rear elevational view of the clam shell gun stock holder in the stowed position;

FIG. 11 is a bottom plan view of the clam shell gun stock holder in the stowed position;

FIG. 12 is a front elevational view of the clam shell gun stock holder in the stowed position;

FIG. 13 is a right side elevational view of the clam shell gun stock holder in the stowed position; and,

FIG. 14 is a left side elevational view of the clam shell gun stock holder in the stowed position.

The broken lines depict portions of a clam shell gun stock holder that form no part of the claimed design.

1 Claim, 14 Drawing Sheets
